UNITED STATES PATENT OFFICE.

ALBERT B. CHURCH AND JAMES P. WARREN, OF SAN FRANCISCO, CALIFORNIA.

ANNOTATOR.

1,377,749.

Specification of Letters Patent.

Patented May 10, 1921.

Application filed May 13, 1919. Serial No. 296,813.

To all whom it may concern:

Be it known that we, ALBERT B. CHURCH and JAMES P. WARREN, citizens of the United States, residing at the city and county of San Francisco and State of California, have invented new and useful Improvements in Annotators, of which the following is a specification.

This invention relates to an attachment 10 for commercial phonographs and particularly pertains to that class of device shown in Patent No. 1,216,232, entitled "Annotators for commercial phonographs" and on which this is an improvement.

15 It is the principal object of the present invention to provide a device adapted to be mounted upon the body portion of a commercial phonograph and which comprises a fixed tray member and a movable marking member, the tray member adapted to receive a memoranda sheet, while the marking member is adapted to mark certain characteristic indicating marks in corresponding positions upon the memoranda sheet, the present invention being particularly concerned with means for readily and clearly marking upon the memoranda sheet any of the desired indicating marks and of controlling the back spacing of the indicator member 25 when desired, all of which is brought about by very simple mechanism which may be conveniently installed and may be easily operated without discommodeing the dictator.

The present invention contemplates the 30 use of a rack carrying a tray and which is secured to the base of a commercial phonograph, and over which a marking head is adapted to be moved as the reproducer head travels along the cylinder, said marking head being provided with a plurality of plungers which carry separate letters adapted to be impressed upon a memoranda sheet carried in the tray.

The invention is illustrated, by way of 45 example, in the accompanying drawings in which:

Figure 1 is a view in front elevation, showing the upper portion of a commercial phonograph and the present invention attached thereto.

50 Fig. 2 is a fragmentary view in rear elevation showing the construction of the back of the tray, the member engaging the reproducer head and the brackets by which it is secured to the tray body.

Fig. 3 is a view in rear elevation show-

ing the marking head and the manner in which a ribbon is secured therebeneath for inking purposes.

Fig. 4 is a view in end elevation showing 60 the commercial phonograph and particularly disclosing the relation of the annotator attachment thereto.

Fig. 5 is an enlarged view showing the marking head and the ribbon supported 65 therebeneath.

Fig. 6 is an enlarged view in section and elevation showing one of the keys of the marking head and the manner in which the type is arranged in alinement, while the 70 keys are staggered upon the key-board.

Referring to the drawings, 10 indicates the base portion of a commercial phonograph upon which are disposed upright standards 11 and 12. One of these standards 75 forms a bearing for a driving shaft 13 upon which is mounted a cylinder mandrel 14. This mandrel extends horizontally between the two uprights 11 and 12 and is adapted to receive cylindrical phonographic 80 records. The standards 11 and 12 are connected at their upper and forward edges by means of a scale 15 which is uniformly graduated throughout its length and bears a definite relation to the phonographic records 85 so that the entire length of record will be divided into minute divisions for convenience in reference work. The standards 11 and 12 also carry a side shaft 15' upon which a reproducer head 16 is adapted to 90 slide. This head is designed to carry a phonographic diaphragm which is suspended over the phonographic record and may be adjusted to either cut the record or to reproduce the sound waves cut thereon. The 95 reproducer head is adapted to be moved along the side shaft 15' by means of a suitable screw feeding member. Formed as a part of the reproducer head is a forward and upwardly extending tube 17 carrying a 100 flexible speaking tube (not shown in the drawings and through which the sound is transmitted to the diaphragm). It will be understood that the foregoing description applies to phonographs of common commercial use and that the present invention is 105 more particularly concerned with an annotating attachment therefor.

The present invention, broadly considered, consists of a fixed or immovable element 18 and a movable unit 19. The fixed unit consists of a rectangular tray 21 which

is formed with a flat body portion and has an upstanding ledge 22 around both ends and across the lower edge. This ledge is provided to act as a retainer for a pad of mem-
5 oranda slips 23 upon which suitable inscrip-
tions may be made as the phonograph op-
erates. Secured between the upper edges
of the end ledges 22 is a guide shaft 24.
This shaft extends the full length of the
10 tray and is provided to guide the movement
of the movable unit 19. By reference to
Fig. 4, it will be seen that a clamping bracket
24' is formed at each end of the tray and
secured to the back thereof. This bracket
15 comprises a pair of semi-rigid fingers which
are clamped together by set screw 25 and
which will grip the opposite faces of the
body plate of the phonograph so that the
tray will be rigidly held in relation to the
20 movable element.

The movable unit of the phonograph at-
tachment comprises a single plate 26 formed
with a plurality of guide sleeves 27. These
25 sleeves are clearly shown in Fig. 6, and are
there seen to accommodate expansion
springs 28 and plunger 29. The plunger
29 reciprocates through the center of the
sleeve 27, as pressure is exerted upon but-
ton 30. The opposite ends of the plunger
30 are fitted with offset shoulders 31 which
carry one or more type, as indicated at 32.
By reference to Fig. 1, it will be seen that
the several sleeves 27 are staggered in re-
lation to each other and thus allow the keys
35 to be very compactly arranged, so that the
keys will be held in equal spaced relation
over the top of the memoranda sheet, as
shown in Fig. 5. It will also be understood
that the shoulders 31 are alternately offset
40 so that the type 32 will be in alinement and
will stand along the center of the plate 26,
thus making it possible for a character to be
inscribed in each of the spaces on the mem-
oranda sheet and in vertical alinement there-
45 across.

As before stated, the movable element 19
is mounted upon a shaft 24 and is there slid-
ably supported by means of a bearing portion
50 34. This bearing portion is clearly
shown in Fig. 5 as being formed as a con-
tinuation of the flat plate 26 and of extend-
ing rearwardly and around the shaft 24.
The opposite end of the plate 26 is formed
55 with a downwardly and inturned portion
35 adapted to constantly rest upon the lower
ledge of the tray and thus be slidably sup-
ported therealong. Formed from the bear-
ing portion 34 of the plate are ears 37 which
extend upwardly and parallel to the main
60 body portion 26. These ears are separated
by a slot 38 which engages a traveling fin-
ger 39. The finger 39 is a part of a clamping
ring 40, secured around the cylindrical
65 tube portion 17 of the reproducer head, and
by which means the movable element 19 is

moved along the guide shaft 24 and over the
tray 18 when the reproducer head is in
motion.

In order that the type 32 may be inked in
a convenient manner, a two-ply type ribbon
70 41 is provided. This ribbon is formed as an
endless band and is adapted to be slipped
over parallel supporting members 42 and 43
which are formed as a part of the body
plate 26. The manner in which this ribbon
75 is supported is clearly shown in Fig. 3. It
will be further noted that due to this pecu-
liar arrangement the ribbon may be readily
removed or renewed as required without
materially molesting the machine. Conven-
80 ience in obtaining access to the ribbon is had
due to the fact that the lower edge of the
plate 26 is not secured to the tray and that
the plate may swing upwardly and pivot
upon the shaft 24 by means of its bearing
85 34 when desired. This pivotal action is per-
mitted by the engagement of the movable
finger 39 with the slot 38 between the ears
37. This also allows the memoranda sheet
90 to be readily removed.

In using commercial phonographs, it has
been found desirable to leave a margin at
the left-hand end of the cylinder so that ad-
ditional notes or instructions may be added
95 to the cylinder as the dictation progresses.
In order that a suitable length of cylinder
may be thus reserved, a spacing spring 43 is
secured to the left-hand end of the tray and
across the back thereof, as clearly shown in
100 Fig. 2. This finger extends outwardly and
is of a width to correspond in the present
instance to five graduations on the scale 15.
This finger is fitted with a key 44 which
may be depressed and which will swing the
105 finger away from the guide rod 24 and per-
mit the bearing portion of the movable unit
19 to travel along the rod 24 until it strikes
the end of ledge 23. This will dispose the
reproducer needle at the extreme left-end
110 of the record and will allow these additional
notations to be made. When the marking
device is, however, moved back to its origi-
nal position the spring finger will move
against the rod 24 and again automatically
space the marker.

It will be evident that memoranda slips
of any desired design might be used, but it
has been found by practice that a memo-
randa slip having fixed longitudinal spaces
therealong is best suited for the ordinary
120 requirements. The upper space is designed
to receive the letter "L" from one of the
type carried by the plunger of the key L
and to indicate the length of the letter dict-
ated. The next space is to receive the im-
pression of the letter "C" which indicates
125 corrections in dictation at any point along
the length of the cylinder. The succeeding
space is marked by the letter "R" which in-
dicates rush work, the next space by the
130

letter "W" which indicates that a wire is dictated from that point, the next space by the letter "P," which indicates a postscript, while the lower line is marked with the letter "X," indicating extra copy. The key 44 is marked with the letters "M. R." to indicate a margin release.

In operation of the present invention, the tray is locked upon the base plate of a commercial phonograph by means of the fastening bracket 24 and, at the same time, the clamping ring 40, with its finger 39, is secured around the tubular portion of the reproducing head. The finger 39 and the slot 38 of the margin head are then brought to register and the machine is ready for operation. As the dictation proceeds the reproducing head will move the length of the record cylinder and will carry the movable unit 19 of the attachment. When a letter has been concluded, the button, or key, "L," is depressed and will thus act to stamp the letter "L" in the column provided for that purpose. In the event that corrections are to be made, the letter "C" may be placed at that point, and will call the transcribing operator's attention to the correction. The other keys may be used as the case requires and as the dictation progresses. The result 30 will be obvious, and it will be understood that, after the record has been dictated, the memoranda slip may be removed from the pad and sent to the transcriber for guidance in the process of typing or writing from the 35 dictation recorded on said cylinder.

It will be evident from reference to Fig. 4 of the drawings that finger 39 registers with the slot 38 in such a manner that the marking member may swing upwardly without becoming disengaged from the finger 39, thus making it possible to swing the marking element upwardly to remove the memoranda sheet and thereafter swing it back into its operative position without 45 changing its position in relation to the traveling element on the phonograph.

It will thus be evident that with the use of the present device a very simple and inexpensive annotator for commercial phonographs is provided which will operate in a direct and simple way to provide an accurate record of the character of the dictation upon a cylinder and give adequate instructions for the final transcription of the work 55 on the cylinder.

While we have shown the preferred form of our invention, as now known to us, it will be understood that various changes in the combination, construction and arrangement 60 of parts may be made by those skilled in the art without departing from the spirit of our invention as claimed.

Having thus described our invention, what we claim and desire to secure by Letters Patent is:

1. In an annotator for commercial phonographs, a fixed tray, a marking element movable thereover, a slotted lug extending upwardly from said element, a finger for engaging said lug and means for supporting the movable element whereby it may swing vertically in relation to the finger without disengagement therefrom, and may move horizontally while in engagement therewith. 70

2. An attachment for a commercial phonograph comprising a fixed tray in relation to the phonograph, a shaft mounted longitudinally on said tray, a marking head slidably mounted thereon, a plurality of depressible type keys carried upon said marking head, a slotted extension member formed at the upper end of said head, and a finger secured to the traveling element of the phonograph and normally engaging in said slot for producing movement of the marking head in relation to the tray, said finger being adapted to permit the marking head to be swung upwardly and about the shaft upon which it is mounted without disengagement therewith. 85

3. In a device of the character described, a fixed tray having a ledge around three sides thereof to retain a pad of memoranda sheets thereon, a guide bar secured between the end ledges of said tray and extending along the upper edge thereof, a marking head slidably mounted upon said bar and adapted to move across the tray, the lower end of said marking head being slidably supported upon the ledge of the tray, a plurality of depressible keys carried on said marking head and a receiving pad carried by the marking head, a slotted extension member formed at the upper end of said head, and a finger secured to the traveling element of the phonograph and normally engaging in said slot for producing movement of the marking head in relation to the tray, said finger being adapted to permit the marking head to be swung upwardly and downwardly and about the shaft upon which it is mounted without disengagement therewith. 100

4. An annotator for a commercial phonograph comprising a tray adapted to be detachably fixed to the base portion of the phonograph, a guide shaft secured along the upper edge of said tray, a marking head slidably supported upon said shaft at its upper end and adapted to rest upon the lower edge of the tray for further sliding support, said marking head being pivoted upon the shaft so that it may swing upward and away from the tray when desired, a slotted lug formed as a part of said marking head, a finger adapted to engage the slot of said lug, said finger being secured upon a traveling element of the phonograph and adapted to permit the upward and downward swinging of the marking head with- 115 120 125 130

out disengagement with the slot in which it is disposed.

5. In an annotator for commercial phonographs having a horizontal traveling element, a fixed frame, a marking element movable thereon, means for supporting said marking element whereby it may move horizontally and its lower end be free to swing upward and downward in an arc, and extension means for the traveling element of the phonograph and marking element whereby the marker may be drawn in either direction by the traveling element of the phonograph,

each of said extension means being free with respect to each other, and adapted to permit 15 the upward and downward swinging movement of the marker without being disengaged.

In testimony whereof we have hereunto set our hands in the presence of two sub- 20 scribing witnesses.

ALBERT B. CHURCH.
JAMES P. WARREN.
